FREQUENCY DOUBLER

Henry Shore, Brooklyn, N. Y., assignor to Radio Corporation of America, a corporation of Delaware

Application June 22, 1937, Serial No. 149,647

1 Claim. (Cl. 250—36)

This application concerns a new and improved means for multiplying or doubling the frequency of wave energy of any form of frequency derived from any source. A feature of my means 5 is the use of aperiodic circuits in a frequency doubling system. Of the many advantages of this use of aperiodic circuits or means for doubling the frequency of wave energy a large number are apparent and others will appear from the 10 detailed description of my invention which follows.

In describing my invention reference will be made to the attached drawing wherein,

Figures 1 and 4 illustrate two circuit arrangements each including the essential elements of my frequency doubler. Additional amplifying or doubling means or both may be added;

Figure 2 is a curve illustrating the grid current plate voltage characteristic of an electron discharge tube operated in accordance with my invention; and

Figure 3 illustrates the plate input current of original frequency and the grid output current of double frequency.

Referring to Figure 1 wave energy of any frequency from any source 2 may be impressed on the anode 8 and cathode 12 of an electron discharge tube 4. This input anode circuit includes no source of potential and may be coupled inductively to the source 2 as indicated, or may be coupled in any approved manner to the source 2. The control grid 10 is coupled to an output circuit 6. This circuit includes a direct current branch comprising an impedance 9 and source of potential 14 which impresses a positive potential on the control grid 10 relative to the cathode 12 and an alternating current branch comprising a coupling condenser 11 and a reactance 13. This latter branch may be coupled in any manner to the load circuit, such as for example, capacitively, or inductively as illustrated. The load 16 may include amplifiers or additional doublers and amplifiers. The wave energy of frequency f impressed by 2 on the input circuit of 4 is doubled, due to the characteristics under which tube 4 operates and the double frequency $2f$ appears in 6 and 16. The doubler, including its input and output circuits, may be aperiodic, or un-

tuned, and this is an important feature since the changing of the frequency to be doubled does not necessitate changing of tuning of the doubling circuits. Preferably for the sake of selectivity one or more of the circuits following 6 or 5 including 6 may be tuned to the double frequency. In case efficiency is a requirement the input circuit may be tuned in any manner such as by condenser 18 as shown in Figure 4.

The operation of my frequency doubler as described above, depends on the grid current plate voltage characteristic of the tube 4 which is as indicated in Figure 2. The plate voltage is varied in accordance with the wave energy supplied from 2 only and with a constant positive potential e_g on the grid of the tube supplied by 14, the tube has a conical characteristic as indicated. The output alternating current in the circuit 10, 14, 12 is of double frequency and is superposed on a steady direct current plate component, unless means such as 9 and 11 is provided to separate the direct current and alternating current components. Thus, where capacitive coupling is used, as in Figure 1, the coupling capacity will block and remove the direct current component from the output.

In a preferred modification as illustrated in Figure 4 the direct current component is bucked out by connecting a second source 20 and variable resistance 22 in shunt to 9 to produce a current i_b which opposes and bucks out current i_p .

I claim:

In a system for doubling the frequency of wave energy, an electron discharge device having an anode and a cathode, means for coupling said anode and cathode to a source of said wave energy only, said electron discharge device having a grid, an output circuit coupled only to said grid and cathode, means for applying a positive potential to said grid relative to said cathode whereby wave energy of double the frequency of the wave energy of said source is produced in said output circuit and means including a variable resistance and a source of potential connected in said output circuit to buck out the direct current component produced therein.

HENRY SHORE.
